FUEL INJECTING MEANS FOR INTERNAL-
COMBUSTION ENGINES

Hilding Gunnar Camner, Ektorp, Sweden, assignor to Aktiebolaget Atlas Diesel, Stockholm, Sweden

Application July 3, 1941, Serial No. 400,946
In Sweden July 8, 1940

11 Claims. (Cl. 299—107.2)

In internal combustion engines, above all, high speed engines with direct fuel injection, it is very difficult to attain a smooth operation and desired control with the injection valves now generally used. The difficulties are due to the fact that the valve spring must be loaded to a comparatively high pressure, in order that the valve shall permit of being closed rapidly so as to overcome the pressure of the gases in the combustion chamber after the fuel pump has been unloaded.

Through the high loading pressure the atomization will keep rather constant during the injection period. When the ignition then commences, it therefore takes place well-nigh in the way of an explosion, which involves a rough operation of the engine.

At a low number of revolutions and a low load, the high loading pressure is disadvantageous also from the point of view of control. By reason of the volume of the fuel pipes and the fuel pump, and on account of by-leakage within the fuel pump, the difficulties in obtaining accurately adapted injection quantities are increased. In idle running, above all, it therefore frequently occurs that the engines are caused to operate at fluctuating speed.

The present invention has for its object to obviate the above mentioned drawbacks, and substantially consists in that the oil pressure from the fuel pump is caused to actuate the spring of the injection valve by the aid of at least two pressure members movable in separate chambers communicating with the fuel pump, one of said chambers being in communication with the engine cylinder through the injection valve, and with the fuel pump through the intermediary of a valve contrivance.

The accompanying drawings illustrate some embodiments of an arrangement in accordance with this invention. Fig. 1 is a longitudinal section of a fuel pump and an injection valve connected thereto according to one embodiment. Fig. 2 is a similar section according to a modified construction. Fig. 3 is a longitudinal section of an injection valve according to a second construction, and Fig. 3a is a section of an appurtenant detail taken on a plane forming an angle to the sectional plane according to Fig. 3. Figs. 4 and 5 show longitudinal sections of a portion of the fuel pump according to some modified embodiments. Fig. 6 is a longitudinal section of an injection valve with a fuel pump built together therewith directly. Figs. 7, 8 and 9 show some embodiments of a needle-valve member. Fig. 10 shows a longitudinal section of a fuel pump according to a

further embodiment. Fig. 11 is a longitudinal section of an injection valve according to still further modified embodiment, and Figs. 12 and 13 are similar sections of two further modifications of the injection valve.

The fuel pump shown in Fig. 1 is of known construction and consists of the pump housing 1 with the piston 2 operating therein and with passages 3 communicating with a fuel container (not shown) and the pump chamber 18. A pressure valve 6 actuated by a spring 5 is arranged in the pump head in known manner.

The injection valve is designated by 9 and the atomizer thereof by 10. The outlet through the atomizer is controlled by a needle valve member 11 constructed as a differential piston having the smaller piston 12 arranged in a lower chamber 13 and the larger piston 14 in an upper chamber 15. The chamber 13 communicates with the fuel pump chamber 18 through a passage 16 in the valve housing, a conduit 17 and the outlet controlled by the pressure valve 6, while the chamber 15 is in direct and permanent communication with said pump chamber through a passage 19, a conduit 20, and a passage 21 in the pump head. The needle valve is urged to closed position by a compression spring 22. A needle valve made in one piece as a differential piston as stated above is shown in detail in Fig. 7.

When at its pressure stroke the pump piston 2 closes the passages 3, 3 in the pump housing, the pumping commences so as to cause the fuel to flow past the opened pressure valve 6 through the conduit 17 and the passage 16 into the chamber 13 of the atomizer 10, as well as through the passage 21, the conduit 20, and the passage 19, into the chamber 15 underneath the larger piston 14 of the injection valve. When in the chambers 13 and 15, operating in parallel, the pressure has risen to a value exceeding the pressure of the spring 22, the needle will open the outlet ports of the atomizer 10, so that the injection into the engine cylinder commences. On account of the construction of the needle valve as a differential piston having the fuel pressure acting on both pistons, the requisite opening pressure will be comparatively low, and by the resistance of the atomizer outlets the fuel pressure will be successively increased during the continued injection. At the termination of the injection, when the pump piston 2 uncovers the passages 3 and the fuel pump is suddenly relieved of pressure, the pressure on the piston 14 of the injection valve will disappear almost entirely, inas-

much as the piston chamber 15 is in direct open communication with the pump chamber 18.

This involves that, in difference from the arrangements hitherto known, the opening pressure can be kept very low. When the pressure on the fuel is augmented during the continued injection, the atomization of the fuel will become different at the commencement and the termination of the injection so that, when the ignition sets in, all of the oil particles will not be combusted at the same rate, a more extended combustion being obtained instead, whereby the rise of the pressure within the engine cylinder becomes less violent and the operation of the engine softer in consequence thereto. In idle-running and at low loads, more uniform injections will be obtained by reason of the low pressure, which brings about an improvement as regards the control.

By dimensioning the spring 5 in a manner such that the valve 6 will open only at a higher pressure than does the needle valve 11, a pre-injection may be effected through the expansion of the fuel as soon as the needle valve opens, provided the remaining pressure in the chamber 13 and in the passages 16, 17 is higher than the gas pressure within the engine cylinder. The principal injection will set in only after the pressure in the pump has risen to a value exceeding the pressure of the spring 5.

The quantity of the pre-injected fuel will depend, in addition to the magnitude of the remaining pressure, on the volume of the passages 13, 16 and 17. The time between the pre-injection and the principal injection is dependent on the volume existing in the pump chamber, the passages 19, 20, and the chamber 15.

The pre-injection may entail a combustion still more extended, whereby the operation of the engine is further improved.

The embodiment shown in Fig. 2 differs from that one according to Fig. 1 only in that a further valve is provided in the conduit between the pump chamber 18 and the valve chamber 13, said valve being constituted by a pressure reducing valve 8 actuated by a spring 7 and intended at the unloading of the pump primarily to bring about a reduction of the pressure in the chamber 13 and the conduit 16, 17 and then to maintain a desired pressure therein.

This pressure will stop at a value determined by the tension of the spring 7. The pressure on the piston 14 having been removed, and the power of the spring 22 being thus only counteracted by the pressure on the piston 12, the valve 11 will be capable of closing at a pressure in the chamber 13 exceeding the opening pressure to a substantial extent. It will thus be possible to bring about a sure and rapid closure of the communication to the engine cylinder, even if the opening pressure on the injection valve would be lower than the pressure within the said cylinder.

The spring 7 acting upon the pressure reducing or return valve 8 may be loaded in a manner such that the remaining pressure in the chamber 13 is kept somewhat higher than the maximum pressure in the engine cylinder, so that the gases in the latter are prevented from entering the injection valve.

It is also possible, however, to choose the tension of the spring 7 so that the remaining pressure in the chamber 13 becomes lower than the compression pressure in the engine cylinder prevailing prior to the opening of the needle valve.

In this case, the air compressed within the

cylinder will penetrate into the chamber 13 a moment after the opening of the needle valve so as to heat the fuel in said chamber. When the injection is then taking place, the first fuel particles will be caused to ignite at a much earlier stage than the remainder of the injected fuel. Hereby a successive combustion will be obtained, which brings about a smoother operation of the motor.

10 Figs. 3 and 3a show another embodiment, wherein corresponding details have been given the same reference numerals as in Figs. 1 and 2.

Here, the needle valve proper is of a different construction, inasmuch as the needle 11 with the 15 piston 12 and the piston 14 are made as separate parts with a certain radial clearance provided between the two pistons. The object of this arrangement is to facilitate the fitting of the two pistons into their guideways, in case complete 20 concentricity would not exist in the manufacture of the valve body and the piston guideways. The separate external piston is tightly pressed by means of a spring 23 against an annular abutment 24 on the piston 12, so that the two pistons 25 will act as a unitary differential piston. This valve construction is shown in detail in Fig. 8.

In the embodiment according to Figs. 3 and 3a, the injection valve is further provided with a spring-actuated pressure valve 25 and a return 30 valve 26, likewise spring-actuated, said valves controlling the inlet 27 and the outlet 28, respectively, of the chamber 13 in the atomizer, the same being adapted at certain pressures to bring about communication with an annular passage

35 29 provided in the valve housing, said passage communicating with the fuel pump through the passage 16 and the conduit 17. The annular passage 29 furthermore communicates directly with the chamber 15 underneath the larger valve piston 14 through a passage 30, Fig. 3a. Here, the injection valve has a single connection only with the fuel pump, that is to say the conduit 17 forming a common inlet to the two chambers 13 and 15. Consequently, no separate supply conduits, as in the embodiment according to Fig. 1 or 2, are required here, the passage 19 in the fuel 40 valve, the conduit 20 and the passage 21 in the fuel pump being here dispensed with entirely.

Otherwise, the fuel pump may be arranged 45 either as shown in Fig. 1 or 2, or, it may be entirely valveless, as shown in Fig. 4, or may be provided with a pressure reducing valve 31, as shown in Fig. 5.

If the fuel pump is entirely without valves, particularly without a pressure valve, a feed pump should be employed, which maintains a pressure of a few atmospheres on the supply conduit to the fuel pump.

In the embodiment according to Fig. 3, the 60 pressure valve 25 serves to cut off the injection chamber 13 from communication with the fuel pump at the unloading thereof, whereas the return valve 26 may replace a corresponding valve in the fuel pump. Here, the spring pressure on the valve 26 may be selected of such a value that,

65 when the return passage 28 is cut off, the remaining pressure in the atomizer chamber 13 will exceed the maximum pressure in the engine cylinder. If a return valve is provided in the fuel 70 pump according to Fig. 2, spring 7 of such valve should have a lighter tension than the return valve 26.

The spring tension for the pressure valve 25 may then, as in the pressure valve 6 according to Fig. 1, be selected so that the valve 25 is caused to

open only at a higher pressure than does the needle valve 11, so that a pre-injection will first be effected, followed by a principal injection.

With the use of a pressure valve 31 in the fuel pump according to Fig. 5, in combination with a fuel valve according to Figs. 1 or 3, 3a, the valve 31 may be constructed as a pressure reducing valve, as shown in Fig. 5. To this end, the valve 31 is provided in known manner with a cylindrical portion 32 making a tight fit with the surrounding wall of the pump head 4.

Here, at the pressure stroke of the pump, the pressure valve 31 must first be lifted to such a level that the lower edge of the cylindrical portion 32 is brought above the valve seat, before the valve admits the fuel to the injection valve. When the fuel pump is then unloaded, the valve is moved back by the spring 5 and the pressure in the conduit to the injection valve so as to cut off the passage at the valve seat, as soon as the lower edge of the cylindrical portion 32 moves below said seat. The valve 31 then moves a further distance downwardly, until it bears on the seat. Hereat, the volume of the pressure conduit is augmented, which results in that the pressure in the conduit drops.

Otherwise, the effect of the injection valve according to Figs. 3, 3a combined with a fuel pump according to any of the embodiments in accordance with Figs. 1, 2, 4 and 5 is in principle the same as that described in connection with the embodiment according to Fig. 1, because, when the needle valve is opened, the fuel pressure will at the same time act upon the pistons 12 and 14, while at the relieving of the fuel pump the larger piston 14 will also be relieved of pressure.

The valves 25 and 26 in Fig. 3 may also be replaced by other valves, for instance of a pressure-reducing type, such as the valve 31, 32 according to Fig. 5.

Fig. 6 shows an embodiment wherein the injection valve and the fuel pump are built together. Here, a channel system 33 leads from the pressure chamber 18 of the pump to an annular channel 34 formed in the lower portion of the pump housing. The channel 34 is, through a passage 35, in direct communication with the chamber 15 underneath the larger needle valve piston, and is also, through an outlet controlled by a pressure valve 36, in communication with a second annular channel 37 formed in the housing of the fuel valve, said latter channel communicating through a number of passages 38 with the chamber 13 in the atomizer. Here, the valve 36 is of a pressure-reducing type and constructed in the same manner and with the same effect as that of the valve 31, 32 in Fig. 5. The needle valve pistons 12 and 14 are formed here as separate parts. Provided in the upper larger piston 14 is a radial incision 39, the lower portion 40 being bifurcated. Radially introduced into this fork is the lower piston 12 which is provided with a head 41 fitting into the radial incision. This valve construction is shown in detail in Fig. 9, and has the same object as the construction according to Fig. 8. The effect of the combined fuel pump and injection valve is the same as that one above described.

Fig. 10 shows a fuel pump which, like that one according to Figs. 1 and 2 respectively, has two separate outlet conduits 17 and 20, the first of which is valve-controlled, while the second is in direct open communication with the pump chamber 18. However, the pressure and return valves have been replaced here by a pressure reducing valve 31, 32 with pressure reduction of the same

type and effect as the valve shown in Fig. 5. This fuel pump may preferably be used in connection with an injection valve of the type shown in Figs. 1 and 2.

Fig. 11 shows an embodiment of an injection valve with two entirely separate controlling pistons, that is to say, the ordinary piston 12 on the needle valve 11, as well as a second piston 43, the piston chamber 44 of which is formed, in the embodiment shown, in the ordinary screw plug 45 while communicating through a passage 46 with the conduit 16, 17 to the fuel pump. The piston 43 is actuated by a spring 47 and, in turn, actuates the compression spring 22 of the needle valve 11 through a plate 48. Otherwise, the injection valve is constructed in the same manner as in the embodiment according to Fig. 3, with a pressure valve 25 and a return valve 26, and with a supply passage 27 to the piston chamber 13 and an outlet passage 28 therefrom.

The opening pressure for the needle valve 11 is determined by the tension of the spring 22 thereof. This tension is determined here by the compression spring 47 loading the piston 43 and thus indirectly the needle valve spring 22. At the pressure stroke of the fuel pump the fuel pressure will act partly on the piston 43 and partly, after the pressure has opened the valve 25, on the piston 12. By the pressure on the piston 43 the latter will be moved upwardly, the spring pressure on the needle valve being thus reduced, which results in that the latter will open the connection through the atomizer 10 at a comparatively low pressure. When the fuel pump is relieved of pressure, the pressure in the piston chamber 44 ceases entirely or in part, in the same manner as in the piston chamber 15 according to the embodiments above described, and the piston 43 is moved by the spring 47 into its lower position, which results in that the needle valve spring 22 is strained so that, depending on the spring tensions chosen, the needle valve will close at a pressure in the chamber 13 equaling or exceeding the opening pressure for the needle valve.

Here, too, the spring tension for the pressure valve 25 may be selected so, if desired, that pre-injection is caused to take place.

Fig. 12 shows an embodiment of the injection valve which differs from that one shown in Figs. 3, 3a only in that the needle valve 11 has a single piston only, that is to say the upper larger piston 14, which will thus primarily take care of the opening of the needle valve. As soon as this valve and also the pressure valve 25 have been opened, the needle 11 proper will act as a pressure piston, however.

In the embodiments of the injection valve above described, an outwardly opening needle valve has been made use of. Obviously, however, the valve 11 may be of some other construction, for instance of the inwardly opening type, as shown in Fig. 13.

Here, the valve spindle 59 is provided at its inner end with a conical valve body 50 cooperating with a corresponding control seat in the atomizer 10 and adapted to be moved into closing position by a spring 51. Arranged at the upper end of the valve spindle 59 is a piston 53 displaceable within a space 52, said piston being adapted to be actuated for upward movement by a compression spring 54.

The fuel enters from the pump, which may be of any of the constructions above described, through the passages 17, 16 into the piston space 52, from which leads a passage 55 to the pressure valve 25, at the opening of which the fuel is

conducted through the passage to the lower chamber 13. Return fuel escapes through the passage 28, to which may be connected a return valve in the manner shown in Fig. 3, for example. Leaking fuel may escape through a passage 56. The effect of this arrangement is the same as that described for the embodiments indicated above, because, when the valve is opened, the fuel pressure will act partly on the piston 53 and partly on the valve body 50, while at the closing the upper larger piston 53 will be entirely relieved of pressure, so that closing of the valve will take place quickly. Here, too, pre-injection may be caused to take place by suitably dimensioning the spring actuating the pressure valve 25. No special atomizer openings have been shown here.

Obviously, the invention is not limited to the embodiments above described and illustrated, inasmuch as the injection valve proper with its appertaining piston device, as well as the pressure and return valves cooperating therewith, may be varied in regard to their construction and arrangement within the scope of the invention. Thus the larger auxiliary pistons as illustrated may be replaced by bellows, diaphragms or similar pressure members. Likewise, more than two pressure members may be brought into use.

In combination with the valve constructions as illustrated, a further improvement may be obtained by forming the fuel pump cam 42, Figs. 1 and 6, to a suitable shape, for instance by imparting to the same a slight rise at the beginning of the pump stroke and a more pronounced rise in the continuation thereof, and, again, a slighter rise toward the end of the stroke corresponding to the highest load.

What I claim is:

1. A fuel injection device including a fuel pump of the kind operative to provide a rising fuel pressure and then a sudden pressure drop, a fuel injection valve housing having means forming an injection chamber and a passageway leading from said chamber to injection ports, a valve member movable in said housing and so associated with valve seat means in said passageway as to control flow of fuel through said passageway, loading means acting on said valve member in such a direction as to close said passageway, means providing a communication between said injection chamber and the working space of the pump, means forming a second chamber in said housing separate from said injection chamber, means connecting said second chamber with the working space of the pump, pressure responsive means movable in said second chamber and exposed through said connecting means to fuel pressure from the working space of the pump, said pressure responsive means being associated with said valve member to exert thereon in response to rising pressure in said second chamber an opening force acting in opposition to the closing force exerted thereon by said loading means and operative upon such rising pressure to cause said valve member to move to open said passageway, said opening force being reduced by flow of fuel from said second chamber to the working space of the pump upon said sudden pressure drop in said working space to thereby render said loading means effective for closing said valve member, and a valve device in communication with the injection chamber and the working space of the pump to maintain a predetermined minimum fuel pressure in the injection chamber while said passageway is closed.

2. Fuel injection device as claimed in claim 1 in which the valve device between the injection chamber and the working space of the fuel pump has means associated therewith to provide for the reduction of the fuel pressure in the injection chamber and then to maintain said predetermined minimum pressure therein.

3. Fuel injection device as claimed in claim 1 in which the valve device between the injection chamber and the working space of the fuel pump has means associated therewith to cause the valve device to open in a direction toward the injection chamber upon a higher pump pressure than the pressure required to open the valve member, in order to effect a preliminary injection.

4. Fuel injection device as claimed in claim 1 in which the valve device between the injection chamber and the working space of the fuel pump comprises at least two valves connected in parallel, one for admitting fuel to and one for releasing fuel from the injection chamber, the latter of said valves being a portion of said means for maintaining said predetermined pressure in said injection chamber.

5. Fuel injection device as claimed in claim 1 in which the valve device between the injection chamber and the working space of the fuel pump comprises at least two valves arranged in parallel, one for admitting fuel to the injection chamber and one for releasing fuel from the injection chamber and in which the valve for releasing fuel from the injection chamber has means associated therewith for loading it to first reduce the fuel pressure in the injection chamber upon the falling pressure and thereafter maintain said predetermined minimum pressure in said chamber.

6. Fuel injection device as claimed in claim 1 in which the valve device between the injection chamber and the working space of the fuel pump comprises at least two valves arranged in parallel, one for admitting fuel to the injection chamber and one for releasing fuel from the injection chamber and in which the valve for releasing fuel from the injection chamber has means associated therewith for loading it first to reduce the fuel pressure in the injection chamber to a value below the pressure outside the injection ports when the fuel pressure falls and thereafter maintain said predetermined minimum pressure in said chamber.

7. A fuel injection device including a fuel pump of the kind operative to provide a rising fuel pressure and then a sudden pressure drop, a fuel injection valve housing having means forming an injection chamber and a passageway leading from said chamber to injection ports, a valve member movable in said housing and so associated with valve seat means in said passageway as to control flow of fuel through said passageway, a spring acting on said valve member in such a direction as to close said passageway, means providing a communication between said injection chamber and the working space of the pump, means forming a second chamber in said housing separate from said injection chamber, means connecting the second chamber with the working space of the pump, a piston movable in said second chamber and exposed through said connecting means to fuel pressure from the working space of the pump, said piston being associated with said valve member to exert thereon in response to rising pressure in said second chamber an opening force acting in opposition to the closing force exerted thereon by said spring and operative

upon such rising pressure to cause said valve member to move to open said passageway, said opening force being reduced by flow of fuel from said second chamber to the working space of the pump upon said sudden pressure drop in said working space to thereby render said spring effective for closing said valve member, and a valve device in communication with the injection chamber and the working space of the pump to maintain a predetermined minimum fuel pressure in the injection chamber while said passageway is closed.

8. Fuel injection device as claimed in claim 1 in which a pressure responsive means is provided in the injection chamber operative in conjunction with the pressure responsive means of said second chamber to open the valve member in response to a rising fuel pressure.

9. Fuel injection device as claimed in claim 1 in which a differential piston displaceable in said injection chamber and in said second chamber constitutes said pressure responsive means operative to open said passageway in response to rising fuel pressure in said chambers.

10. Fuel injection device as claimed in claim 1 in which the valve device between the injection chamber and the fuel pump is located in the fuel injection valve housing.

11. Fuel injection device as claimed in claim 1 in which the fuel pump is provided with an operating cam shaped to provide a slight rise at the beginning of a pump stroke and increasing rise thereafter and a decreasing rise toward the end of that part of the pump stroke corresponding to maximum load.

HILDING GUNNAR CAMNER.
